UNITED STATES PATENT OFFICE

2,627,722

HYDRAULIC JACK

Douglas Johnston, Huntsville, Ala., assignor to
 General Fluid Machinery Company, Huntsville,
 Ala., a corporation of Alabama

Application January 29, 1947, Serial No. 725,013

5 Claims. (Cl. 60—52)

1

The present invention relates to a hydraulic jack.

It is an object of the invention to provide a hydraulic jack wherein leaks in the hydraulic mechanism are largely prohibited and wherein the design is such that a solid steel base may be used to reduce the likelihood of leakage. A further object is to provide a particularly desirable valve construction wherein there are brass inserts to form the valve seats for each of the valves, and wherein all of the valves are located in a single opening and are accessible through this opening for replacement. Another object is to provide inserts for the valve arrangement, including seat members and spacers that minimize the number of different parts required.

A further object is to provide a jack of this type wherein the ram can be mounted in the center of the base and the valves disposed in a single opening at one side of the base.

In the drawings:

Fig. 1 is a plan view of the jack;

Fig. 2 is a vertical section on the line 2—2 of Fig. 1;

Fig. 3 is a vertical sectional view taken on the line 3—3 of Fig. 1;

Fig. 4 is a horizontal section looking downwardly on the line 4—4 of Fig. 3;

Fig. 5 is an enlarged sectional view of the valve construction shown in the lower part of Fig. 3;

Fig. 6 is a horizontal section through the valve construction, taken on the line 6—6 of Fig. 3; and

Fig. 7 is a front elevation of the jack, with the ram partly broken away.

The jack includes a base 10 that may be formed of steel in one solid piece. This base 10 has a cut-out in its upper surface into which a cylinder 11 is threaded. A cap 12 is threaded into the upper end of this cylinder, it having a hexagonal wrench fitting portion as shown in Fig. 1. An oil reservoir tubing 13 fits between the cap 12 and the base 10 and is sealed thereto to hold a supply of oil, as indicated in Fig. 2.

The cylinder 11 slidably receives a piston head 15 to which a tubular member 16 is attached. This tubular member is threaded to receive a jack screw 17 which may be turned and thereby adjusted in and out with respect to the cylindrical portion 16. The screw has a head 18 on it which may be disposed beneath the work to be lifted. The head 15, cylinder 16, screw 17 and head 18 constitute the ram of the jack and are centrally located on the base. The head 15 has the usual sealing means 20 on its bottom surface, so that hydraulic fluid forced below this sealing means

2

20 will lift the ram. The cap 12, above the cylinder 11, receives a packing ring held in place by threaded rings 21 screwed into the cap 12 that compress the packing ring and maintain it in contact with the cylinder 16. As the head 15 is larger in diameter than the cylinder 16, the head will engage the lower ring 21, at the upper end of the stroke, and be prevented from moving out of the base.

10 As noted, the tubing 13 provides, with the cylinder 11, the base 10 and the cap 12, an annular oil reservoir 22. The space within the cylinder 11 and the base, below the head 15, constitutes an operating cylinder 23 for the jack.

15 The base is provided with an opening 24 that is drilled thereto from the back part of the base. A sloping continuation 25 of this opening 24 leads to the front of the base and has varying diameters, as will appear.

20 The reservoir 22 has a passage 27 leading into the end 25 of the opening 24. It has another passage 28 that leads into the valve opening 24 toward the other end thereof. Between these two passages, there is a passage 29 that leads 25 into the operating cylinder 23.

Upstanding from a middle part of the opening 24, there is a vertical port 30 that opens into a pressure cylinder 31 threaded into the top surface of the base to one side of the reservoir 22.

30 This member 31 receives an operating plunger 32 having a packing gland cap 33 attached to its end. The plunger rod 32 passes through the cap 33, and is pivoted to a rocking lever 35. The rocking lever is, in turn, pivoted to a vertical lever 36 that is pivoted between brackets 37 on the top of the base. These pivot arrangements comprise removable pins held in place by cotter pins, as shown. The lever 35 has a socket 38 at its outer end. A pin 40 passes through the socket. It will be seen that, when a handle, indicated at H, is inserted in the socket, and the lever 35 is rocked up and down, the plunger will be moved up and down.

45 The opening 24 receives a series of valves, valve seat inserts and spacers. At the left end of the opening in Figs. 5 and 6, there is a valve seat insert 45. The opening 24 is preferably cylindrical, and the insert has an outside cylindrical surface that slides into the opening 24 and substantially seals therewith. The insert 45 has a valve seat recess 46 and an annular projection 47 at the other end, with a fluid passage 48 axially through the insert. A ball valve 50 is engageable with the valve seat.

55 There is a gasket 51 that fits around the ex-

tension 47. To the right of the gasket, there is a cylindrical spacer sleeve 52. This sleeve has an inner, shouldered opening whereby it may receive a coil spring 53 and a ball valve 54, and may conduct fluid from end to end. It also has a plurality of lateral ports 55 at suitable points around its periphery.

Next to the right of the spacer, there is another valve seat element that is identical with the element 45. Then there is a gasket 56 and another spacer 57 that is identical with the spacer 52. There is a spring actuated ball check valve 58 that may be received in the sleeve and which cooperates with the valve seat of another valve seat element 59.

Next, there is another gasket 60 followed by two spacers 61 and 62. The right end of the spacer 62 receives a washer 63, against which a solid spacer 64 is engaged. This spacer 64 acts against a gasket 67 identical with the gasket 51. The assembly is held by a threaded plug 65 that has a wrench receiving opening 66 therein. It may be seen that all of the spacers, gaskets, and valve seat elements are thus held in position firmly when the plug 65 is tightened into place, and that the several gaskets are spread into sealing relationship with the walls of the opening 24.

In the extension 25 of the opening 24, there is a manually movable plunger 68 that is threaded into a packing gland fitting 69 that, in turn, is threaded into an enlargement of the opening 25 of the base, and is adapted to compress packing 70. The plunger 68 has a head 71 that is received in an enlarged socket portion 72 of the opening 25. This head 71 is shaped to be received in an internal opening in the end of the handle H, that also engages within the sleeve 38 of the operating lever. The head has a cross pin 74 that is similar to the cross pin 40 in the socket 38.

The disposition of the valve parts provides that the valve 50 will be held against its seat 46 in the seat member 45 by the plunger 68, when the plunger is turned down by rotation of the head 71. This prevents communication from the port 27 that extends to the reservoir to the other parts of the opening.

The opening 28 leads through the ports 55 of the spacer 61 into the interior of these spacers, and thence may flow up against the ball valve 58. The passage 29, that communicates into the pressure cylinder 23, connects into the spacer 52 and through the ports 55 thereof to establish communication of the pressure cylinder with the space between the two valves 50 and 54.

The interior of the operating cylinder 31 communicates through the port 30 with the interior of the spacer 51 to the left of the valve 58 and to the right of the valve 54. There are a sufficient number of ports 55 around each spacer to insure communication from the several passages, as indicated.

At a desired elevation along the casing 13, there is a filler plug 76 through which hydraulic liquid may be inserted. This plug establishes a proper liquid level.

Operation

When it is desired to use this jack to lift some work, the jack is disposed under the work with the jack screw 17 screwed out manually to establish engagement or approximate engagement between the head 18 and the work to be lifted. Thereupon, a suitable pipe handle H, with the necessary notch to engage over the pin 40, is inserted in the socket 38. When the handle is lifted, 75

the plunger 32 is elevated, establishing a low pressure condition back of the valve 58. This causes the hydraulic fluid to be drawn through the passage 28 from the reservoir 22, unseating the valve 58 in this process, so that, when the plunger 32 reaches its top point, the cylinder 31 is properly charged with hydraulic fluid. Upon subsequent depression of the hand lever and the plunger 32, the oil thus drawn in is forced outwardly from the cylinder 31. The valve 58 then seats, checking the flow-back of this oil into the reservoir. The oil under pressure, however, unseats the valve 54 against its spring and passes out the ports 55 into the passage 29 of the cylinder 23, where it can act below the ram head 15. It thus causes the head to be raised. When the plunger reaches the bottom of its stroke, the pressure thus applied is relieved and the valve 54 reseats, checking the outflow of such oil. Thereupon, the cycle is repeated until the work is elevated as far as desired.

When it is desired to lower the jack, the handle is removed from the socket 38 and is inserted over the head 71 of the plunger 68. It is turned to unscrew the plunger and withdraw it from the valve 50 which has been maintained on its seat by the plunger 68. The pressure of the ram downwardly on the hydraulic fluid in the cylinder 23 causes this fluid then to flow past the valve 50 into the passage 27 and back into the reservoir, so that the jack is lowered.

In servicing the jack, the principal members subject to wear are readily accessible. When it is desired to remove the ram, the threaded members 21 and the packing ring are withdrawn. Then the ram may be pulled out, and, if it is necessary to replace the washer 20, the same may be readily done by removing its retaining screw as indicated by the drawing. Thereupon these parts may be conveniently replaced.

In similar fashion, the operating plunger 32 may be removed, as the several levers are held together by cotter pins. When the pins are removed, the gland nut 33 may be unscrewed and the plunger drawn out through the packing and its parts repaired. If need be, the whole cylinder 31 may be unscrewed and repaired or replaced.

The valve arrangement provides for very easy service with a minimum number of different types of repair parts. This comes about because, in the first place, all of the valves are immediately accessible when the plug 65 is withdrawn. Also, the valve seat inserts and spacer sleeves are all duplicates, so that only two types of such parts are required. The gaskets 51 are conventional. All of the ball valves are identical. The pressure relieving means, consisting of the plunger 68 and associated parts, are self-compensating for all normal wear because of the threaded arrangement.

What is claimed is:

1. In a jack, a base, a hydraulic fluid reservoir, an operating cylinder, a ram in the operating cylinder, a pressure cylinder, a pressure producing means in the pressure cylinder, an elongated, cylindrical opening of constant cross section extending at least partially through the base and having an entrance at one surface of the base, a first passage from the opening to the reservoir, 65 a second passage from the opening to the pressure cylinder, a third passage from the opening to the operating cylinder, a fourth passage from the opening to the reservoir, removable valve means in the opening between the first and second passages, removable valve means in the

opening between the second and third passages, and removable valve means in the opening between the third and fourth passages.

2. In a jack, a base, a hydraulic fluid reservoir, an operating cylinder, a ram in the operating cylinder, a pressure cylinder, a pressure producing means in the pressure cylinder, an opening in the base having an entrance at one surface of the base, a first passage from the opening to the reservoir, a second passage from the opening to the pressure cylinder, a third passage from the opening to the operating cylinder, a fourth passage from the opening to the reservoir, valve means in the opening between the first and second passages, valve means in the opening between the second and third passages, and valve means in the opening between the third and fourth passages, said valve means being disposed longitudinally within the opening in abutting relationship.

3. In a jack, a base bounded by a plurality of intersecting surfaces, a hydraulic fluid reservoir, an operating cylinder, a ram in the operating cylinder, a pressure cylinder, a pressure producing means in the pressure cylinder, an opening extending at least partially through the base and having one end thereof terminating at a surface so as to provide an entrance into the opening, a first passage from the opening to the reservoir terminating at a surface of the base so as to provide an entrance into the first passageway, a second passage from the opening to the pressure cylinder, a third passage from the opening to the operating cylinder terminating at a surface of the base so as to provide an entrance 35 into the third passageway, a fourth passage from the opening to the reservoir terminating at a surface of the base so as to provide an entrance into the fourth passageway, a fifth passage from the opening to a surface of the base, valve means in the opening between the first and second passages, valve means in the opening between the second and third passages, valve means in the opening between the third and fourth passages, manually operative valve actuating means in 45 the fifth passage, and means closing the entrances of the opening and the passages.

4. In a jack, a base bounded by a plurality of intersecting surfaces, a hydraulic fluid reservoir,

an operating cylinder, a ram in the operating cylinder, a pressure cylinder, a pressure producing means in the pressure cylinder, a straight opening extending at least partially through the base and having an entrance at one surface of the base, three separate lateral passages connecting the opening with the reservoir, the pressure cylinder and the operating cylinder, respectively, and substantially identical valve means disposed in the opening in abutting relationship so as to control the flow between adjacent lateral passages, each of said valve means including a valve seat, a valve element cooperable with the valve seat, and a spacer, the valve seats being interchangeable, the valve elements being interchangeable, and the spacers being interchangeable.

5. In a jack, a base bounded by a plurality of intersecting surfaces, a hydraulic fluid reservoir, 20 an operating cylinder, a ram in the operating cylinder, a pressure cylinder, a pressure producing means in the pressure cylinder, a straight opening extending at least partially through the base and having an entrance at one surface of the base, four separate lateral passages connecting the opening with the reservoir, the pressure cylinder, the operating cylinder, and the reservoir, respectively, and substantially identical valve means comprising a valve seat, a valve element cooperable with the valve seat, and a spacer disposed in the opening so as to control the flow between adjacent lateral passages.
